DISPLAY FOR CUT FLOWERS AND POTTED PLANTS

Robert W. Crowe, 4942 Encinita Ave.,
Temple City, Calif. 91780

Filed July 19, 1972, Ser. No. 273,336

Term of patent 14 years

Int. Cl. D20—02

U.S. Cl. D6—148

FIG. 1.

FIG. 2.

FIG. 3.

FIG. 1 is an isometric view of a display for cut flowers and potted plants embodying my new design;

FIG. 2 is a side elevational view of the same;

FIG. 3 is a top plan view of the same.

The bottom of the display is plain and unornamented.

I claim:

The ornamental design for a display for cut flowers and potted plants, substantially as shown and described.
